UNITED STATES PATENT OFFICE

SOL FISHER, OF CLEVELAND, OHIO

HAIR WAVING AND CURLING ROD

Application filed April 25, 1932. Serial No. 607,413.

The objects of the invention are to provide an improved form of construction for a permanent marcel waver, or curler, by means of which the waves can be made deeper and fuller and have a less artificial appearance than that of the flat permanent waves now produced by machines upon the market.

By means of this device, hair waves are produced which are laterally extended alternately in opposite directions thus producing alternating fluffy ridges and hollows giving a perfect marcelled effect to the dressed hair.

The invention comprises a waving and curling rod having an attaching means at its scalp end for securing firmly a strand of hair thereon, said rod having a wide helix thereabout, between the projecting blades of which the strand of hair is tightly wound, the sides of the blades being inclined toward the central axis or the rod surface, the intervening grooves being deep enough to enclose a strand and to form it into substantially non-symmetrical wedge shape in cross section, with greater depth along one edge of the strand than along the other, thus producing a fuller and more raised effect when it is released from confinement in the electric heater, any suitable form of which may be employed.

The pitch of the helix and the inclination of opposite sides of the blades thereof to each other are so proportioned as to produce a pronounced wave in one direction alternating with a reversely extended wave.

The inclined surfaces of the helix also serve to draw the strands of hair into the grooves and to compact them, so that when subjected to heat, they will retain a definite marcelled effect with the appearance of increased depth and fullness.

The invention is an improvement upon my previous application Ser. No. 563,685 filed September 19th, 1931, for an improvement in waving and curling rod, and as in that invention the strand of hair wound upon the rod may be wrapped in the usual manner in a moistened flannel cloth and enclosed in tin foil and inserted in an electrically heated tube.

Also a solution may be applied that will soften the hair under the action of steam.

In use the steam is applied to the hair upon the rod for several minutes until the hair becomes perfectly shaped or molded upon the rod, after which it is cooled and removed from the rod and the wave will be permanently set. In this manner greater depth of wave toward and from the head, as well as wide alternately reversed waves are produced.

To accomplish these and other useful results, the invention comprises the combination and arrangement of parts and construction and formation of the various details hereinafter more fully described, illustrated in the accompanying drawing and particularly pointed out in the claims.

In the accompanying drawing, Figure 1 is a perspective showing the appearance of a permanent marcel wave made according to my invention; Figure 2 is a front elevation of one form of my improved rod; Figure 3 is a side elevation thereof; Figure 4 is a side elevation of the hook that clamps the hair upon the rod and acts as a guide to the winder; Figure 5 is a side elevation, partly in section, showing the manner of compressing the hair to increase the fullness of hair at one side of the strand; Figure 6 is a perspective view, showing the clamping device; Figure 7 illustrates my rod with a strand of hair wound thereon and enclosed within a heating implement; and Figure 8 is a longitudinal sectional view, illustrating a modified form of rod.

In these views 1 is a cylindrical rod about the outer portion of which is formed a wide helix 2, the pitch of the blade or blades thereof being chosen according to the desired length of the wave to be produced.

These blades are provided with inclined upper and lower sides 3 and 4 respectively, which converge towards surface or axis of the central stem 5, which may be smaller than the remaining portion of the supporting rod to utilize all the space possible for the formation and compression of the strand.

In use, the strand of hair is first securely clamped upon the outer or scalp end of the rod by means of a hook 6, transversely movable in a guide 7 at the extremity of the rod, and a nut 8, upon the stem 9 of the hook. The

extremity of the hook enters a recess 10 in the first turn of the helix, and the end of the strand is compressed tightly in the groove therein. The hook is prevented from turning by means of the shoulders 12 and 13 upon the guide 7 and the shoulders of the recess 10.

After clamping its scalp end, as described, the strand is wound and compressed tightly 10 in the spiral groove and its outer end is tied or otherwise secured tightly upon the rod at 11. The lower end of the rod as shown in Figure 5, is hinged at 15 to permit it to be extended to serve as a lever or handle for 15 holding the rod. The rod and strand thereon are then subjected to a moist heat in the usual manner.

The helix may be formed with either right or left hand winding as desired. A projecting stop 14 is employed in connection with the automatic guide.

Variation in the shape or arrangement of parts may be made within the scope of the claims.

25 For instance the sides of the helical groove may converge towards the central stem, as before, but may also be more or less recessed or concave, as shown in Figure 8, thus giving a greater fullness to the body of the strand of 30 hair.

It will be observed that with all forms of the invention, the strand of hair is clamped securely at the scalp end of the rod at the entrance to the helical groove or channel lying 35 between adjacent blade portions, the remainder of the strand being wound along the rod in said groove, and the other extremity of the strand being secured to the rod. Since one side of the blade is inclined to the central axis at a more acute angle than the other side, the groove itself, and the strand of hair lying in it, are of non-symmetrical triangular cross section, and the act of winding the strand into the groove, more or less under 40 tension, has the effect of causing the hair to slide down the acutely inclined side of the blade to be forced or pressed toward the more obtusely inclined side of the blade.

As shown in the drawing, I prefer to so arrange the parts that that side of the blade which is the more acutely inclined to the central axis is the nearer to the scalp end of the rod. This arrangement has the effect, as it were, of throwing the hair upwardly or toward the head, thereby producing a deeper and more full wave. The pitch of the helix determines uniformly, with all waves wound upon the same head, the sharpness of the bends or waves of the hair when the molded 50 strand is taken off from the rod after treatment. Hair wound under treatment in the manner described has a tendency to relax, as it were, after being washed and combed out, and the present rod is so arranged as to produce a sufficiently sharp bend or wave, first

in one direction and then in the other, so that when the hair is washed out and combed natural relation will occur, but nevertheless with retention in the hair of sufficient bend or distortion so that a characteristic marcel wave is produced and maintained. Throwing the hair toward the head, in the manner described, gives the strand greater depth along one edge than along the other, with a tendency to increase the depth of the completed wave when lying on the head, with a striking degree of fullness, vigor and life.

It should of course be understood that in the use of these rods on a given head, rods wound right-hand are used upon one side of the head and rods wound left-hand on the other side of the head, and where two rows of rods are employed on one side of the head, as is usually the case, the rods of the first row will be right-hand, for example, and those of the second row left-hand, and so on. In other words, consideration is given to the matching of adjacent waves with each other, so that in the final product all strands, with the waves therein, become a part of an organized entity with a result somewhat after the manner shown in Fig. 1.

Having described the invention what I claim as new and desire to secure by Letters Patent is:

1. In a permanent marcelling and curling device, for strands of hair, a rod, an integral helix thereon, the blade of said helix having wide sides that are inclined inwardly towards their lines of junction with said rod, and forming an intermediate spiral groove in which a strand of hair is tightly wound, and positioned to produce a wide and full outer edge upon said strand, and clamping means for the scalp end of said strand.

2. In a permanent marcelling and curling device, for strands of hair, a rod, an integral helix, thereon, the blade of said helix having wide sides that are inclined inwardly towards their lines of junction with said rod, and forming an intermediate spiral groove in which a strand of hair is tightly wound, and positioned to produce a wide and full outer edge upon said strand, a hooked member provided with a stem transversely movable adjacent to the scalp end of said rod, and means for adjusting said hooked member to clamp the extremity of one of said strands in the scalp end of one of the spiral grooves in said rod.

3. A waving and curling rod, provided with a wide helical blade integrally attached thereto, the sides of said blade being inclined to converge toward the surface of said rod, the inclination of one surface of said blade being greater than that of the other surface, whereby a helical strand of hair wound in the groove in said helix will have a substantially non-symmetrical triangular cross section, for the purposes set forth.

4. A waving and curling rod, provided with a wide helical blade integrally attached thereto, the sides of said blade being inclined to converge toward the surface of said rod, the inclination of one surface of said blade being greater than that of the other surface, whereby a strand of hair wound in the groove in said helix will have a substantially non-symmetrical triangular cross section for the purposes set forth, a projection upon the scalp end of said rod having a horizontal guide opening therein, and a clamping member adjustably movable therein, said clamping member being provided with a depending hook positioned to secure the scalp end of said strand in the end of said groove.

5. A waving and curling rod, provided with a wide helical blade integrally attached thereto, the sides of said blade being inclined to converge toward the surface of said rod, the inclination of one surface of said blade being greater than that of the other surface, whereby a strand of hair wound in the groove in said helix will have a substantially non-symmetrical triangular cross section for the purposes set forth, a projection upon the scalp end of said rod having a horizontal guide opening therein, and a clamping member adjustably movable therein, said clamping member being provided with a depending hook positioned to secure the scalp end of said strand in the end of said groove, the upper turn of said helical blade being provided with a recess for the reception of the lower end of said hook.

6. A waving and curling rod comprising a cylindrical rod portion and a helical portion, said helical portion having wide blades the sides of which converge inwardly towards a central stem, and hooked means at one end of said rod for securing a strand of hair thereto.

7. A waving and curling rod comprising a cylindrical rod portion and a helical portion, said helical portion having wide blades the sides of which converge inwardly towards a central stem, hooked means at the scalp end of said rod for securing a strand of hair thereto, and handle means at the other end of said rod.

8. A waving and curling rod comprising a cylindrical rod portion and a helical portion, said helical portion having wide blades the sides of which converge inwardly towards a central stem, hooked means at the scalp end of said rod for securing a strand of hair thereto, and means for preventing turning of said hooked securing means.

9. A waving and curling rod of the character described in claim 3, in which that surface of the blade which is inclined to the rod surface at the more acute angle is the nearer to the scalp end of the rod.

10. A waving and curling rod of the character described in claim 3, in which the in-

clined surfaces of the blade are slightly concave.

In testimony whereof I affix my signature.
